CLAIM

The ornamental design for a pickup bed as shown and described.

DESCRIPTION

FIG. 1 is a perspective view of the pickup bed;
FIG. 2 is a rear side elevational view of the pickup bed shown in FIG. 1;

FIG. 3 is a right side elevational view thereof; and,
FIG. 4 is a top plan view thereof.

The broken lines in the drawings form no part of the claimed design. A left side elevational view is not shown because it is a mirror image to the right side elevational view shown in FIG. 3.
